(57) **CLAIM**

The ornamental design for a shoe, as shown and described.

DESCRIPTION

The patent or application file contains at least one drawing executed in color. Copies of this patent or patent application publication with color drawing(s) will be provided by the Office upon request and payment of the necessary fee. FIG. 1 is a front and right side perspective view of a shoe, showing my new design;

FIG. 2 is a right side view thereof;

FIG. 3 is a left side view thereof;

FIG. 4 is a front view thereof;

FIG. 5 is a rear view thereof; and,

FIG. 6 is a top view thereof.

The portions of the bottom view that are not shown form no part of the claimed design.

1 Claim, 6 Drawing Sheets
